OPAQUE GAS METER COVER

Kenneth G. Salem, 226 Belmont St.,
Johnstown, Pa. 15904

Filed Oct. 20, 1967, Ser. No. 9,091

Term of patent 14 years

U.S. Cl. D52—6
Int. Cl. D10—99

Fig. 1

Fig. 2

Fig. 3

FIGURE 1 is a front view in elevation of an opaque gas meter cover showing my new design;

FIGURE 2 is an end view in elevation of the design; and

FIGURE 3 is a top plan view of my new design.

The undisclosed side and end of the cover are substantially the same in appearance as the side and end shown.

I claim:

The ornamental design for an opaque gas meter cover, as shown and described.
